UNITED STATES PATENT OFFICE.

LYMAN D. BROUGHTON, OF HARTFORD, CONNECTICUT, ASSIGNOR TO UNDERWOOD TYPEWRITER COMPANY, OF NEW YORK, N. Y., A CORPORATION OF DELAWARE.

TYPE-WRITING MACHINE.

1,069,847.

Specification of Letters Patent. Patented Aug. 12, 1913.

Application filed August 15, 1911. Serial No. 644,132.

To all whom it may concern:

Be it known that I, LYMAN D. BROUGHTON, a citizen of the United States, residing in Hartford, in the county of Hartford and 5 State of Connecticut, have invented certain new and useful Improvements in Type-Writing Machines, of which the following is a specification.

This invention relates to tabulating mechanisms for typewriters and other machines, and particularly to improvements in column skipping mechanism.

In my application No. 585,186, filed October 4, 1910, is illustrated one form of machine in which, by depressing any desired column key, and then depressing any desired decimal key, the carriage of the typewriter is released and arrested at the desired decimal or denominational point in the desired 20 column.

The principal object of the present invention is to simplify and improve the construction and operation of the column-selecting or column-skipping devices, particularly 25 with a view to rendering them more readily adaptable to different types of typewriting machines.

In carrying out the invention, I arrange a series of mounts upon a rack which is attached to the carriage and corresponds to the usual column stop rack on an Underwood typewriting machine. These mounts are independently adjustable along the carriage. Upon these mounts are pivoted 35 column stops, which may be lifted or withdrawn from use by operating said column-selecting keys. Each of these keys is connected to a cam, and the cams are adapted to lift the column stops. For this purpose, 40 the column stops are provided with projections which are of graduated lengths, and the cams are so placed that only one of them can engage the projection of greater length, and hence can lift only one column stop. 45 The next cam is placed so that it can lift the two longest projections, and hence can withdraw two of the stops from use; and so on throughout the series. Hence by operating the desired column stop key the carriage 50 may be arrested in the desired column. These cams are arranged one behind another in back of the usual bank of decimal stops, and the column-selecting keys are preferably arranged at the keyboard upon the forward ends of levers, the rear ends of the

latter being connected to the lower ends of upstanding rods, which at their upper ends carry said cams. One of the denominational stops, preferably that which arrests the carriage in position for writing a decimal point, has a lug, and each of said rods has a shoulder, whereby it may lift said lug, and hence position said decimal stop or counterstop. The mounts for the column stops are of simplified and improved construction; each being preferably in the form of a collar to slide upon the rack bar and having an improved releasable dog for engaging the teeth on the rack.

Other features and advantages will hereinafter appear.

In the accompanying drawings, Figure 1 is a rear perspective view of the present improvements applied to an Underwood typewriting machine. Fig. 2 is a front perspective view showing the connection between the rear ends of the column key levers and the lower ends of the upstanding rods which carry the selecting cams. Fig. 3 is a sectional elevation taken from front to rear 80 of the machine. Fig. 4 is a plan of the rear portion of the machine showing the column stops, decimal stops, etc. Fig. 5 is a rear perspective view of one of the mounts which carry the column stops. Fig. 6 is a 85 rear view illustrating one column stop in normal position, and another column stop as elevated or withdrawn by means of one of the key operated cams. Fig. 7 is a detail perspective view, showing one of the mounts 90 opened up to disclose its structure.

Keys 1 are fixed upon the forward ends of levers 2, the latter connected by bell cranks 3 to type bars 4 which swing rearwardly against a platen 5, the platen being mounted on a carriage 6. The carriage is driven by a spring barrel 7, and has a rack 8 to mesh with a pinion 9, the latter connected to an escapement wheel 10 which forms a portion of the usual letter-feeding mechanism 100 of said carriage 6. Decimal tabulating keys 11, at the back of the keyboard, are mounted by means of stems 12 upon levers 13 extending rearwardly and pivoted between their ends at 14, and at their rear ends articulated 105 at 15 to upstanding rods 16, the latter having decimal stops 17 at their upper ends. These stops may be projected by said keys 11 to a position to engage any of a series of column stops 18, mounted upon and adjust- 110

able along a rack 19, which is fixed to the rear portion of the carriage 6. Each of said decimal stop rods 16, has a lug 19^a to engage a universal bar 20, which is fulcrumed at 21 and connected by a link 22 to a lever 23, the latter pivoted at 24, and at its front end having a roll 25 to engage the under side of the letter-feeding rack 8, and lift the same out of mesh with the pinion 9, so that the carriage can run freely under the tension of the spring 7.

Each of the column stops 18 is pivoted at 26 to a mount 27, which is shown in the form of a collar upon the rack bar 19. The stops are pivoted so that one or more of them may be lifted or withdrawn from use at will; and for this purpose, each stop is provided with a projection 28 extending rearwardly therefrom. The stops overlie a nest of four cams 29 placed upon the machine frame in a bracket 30 just back of the decimal stop rods 16. These cams 29 are liftable for the purpose of raising the column stops 18. The rearmost cam 29 can engage only one pin 28, that is, the longest one of the series; said pin being provided upon that column stop 18 which is first to approach the cams 29 during the letter-feeding movement of the carriage; said column stop being seen at the extreme right of Fig. 1. Hence when the rearmost cam 29 is lifted, the extreme right hand stop 18 at Fig. 1 is withdrawn, and hence the second column stop 18 engages whichever decimal stop 17 is elevated. In other words, the first column is skipped. The operation of these stop withdrawing cams 29 is effected by means of upstanding rods 31 connected thereto and preferably formed integral therewith; said rods being lifted by levers 32 extending forwardly beneath the type bars 4, and preferably beneath the levers 13, and having at their forward ends keys 33 in front of the machine. These levers 32 may be hung on the same fulcrum 14 that carries the levers 13. It will be seen that upon depressing the first lever "2", Fig. 1, the rearmost rod 31 is lifted, and hence the rear-most stop is caused to withdraw the first stop 18 in the manner just explained. If the key marked "3" at Fig. 1 is depressed, said key being on the next to the longest of the levers 32, then the second rod 31 from the rear is elevated, together with the second cam 29, and said cam lifts not only the first stop 18, but also the second one, the pin 28^a on the second stop being long enough to be engaged by said second cam, although not long enough to catch upon the first cam 29. Hence the first two columns will be skipped, and the carriage will be arrested at some point in the third column, dependent upon which of the decimal stops is projected by a key 11. If the key marked "4" at Fig. 1 is depressed, the next to the short-

est lever 32 is operated, and hence next to the front rod or stem 31 is elevated together with its cam 29. This cam is far enough forward to engage and lift all of the first three pins 28, 28^a and 28^b on the first three column stops 18, and hence the carriage runs until the fourth column stop engages one of the decimal stops or column stops 17. In other words, the carriage is arrested in the fourth column. If the key marked "5" at Fig. 1 is depressed, the shortest lever 32 is operated, and the foremost stem 31 is lifted, together with its cam 29, and hence all of the first four projections 28, 28^a, 28^b and 28^c are raised as they successively approach the nest of cams 29, and hence they all pass over such counterstop 17 as is projected; the carriage being finally arrested by the fifth column stop 18^a, which need not be provided with any projecting pin. It will be understood that the pin 28^c is only long enough to be engaged by the front cam 29, while the pin 28^b is long enough to be engaged by the two front cams and so on, the pin 28 being engageable by all the cams.

That decimal stop rod 16 which is seen at the right of Fig. 1, is provided with a universal lug 34 projecting backwardly over a series of shoulders 35 formed upon all of the cam rods 31, so that whenever any of the column-skipping keys 33 is operated, this counter stop rod 16 is elevated. The stop 17 on said rod is the same as is usually employed for arresting the carriage at the position for writing the decimal point; that is, it is the last one approached by the carriage 6 as the latter is moving in letter-feeding direction. Of course, if any of the other decimal tabulating keys 11 is operated, a corresponding stop 17 will be set in advance of the decimal stop projected by the lug 34, and hence the latter will not come into use. It will be understood that the selected key 33 may be depressed at the same time as the selected key 11; and both keys 33 are to be held down until the carriage 6 is arrested in the desired column by the desired decimal stop 17. Upon the relief of the keys from pressure, the column-skipping key is returned by one of a series of individual springs 35, while the decimal key lever is returned by one of a series of springs 36. The usual spring, not shown, is employed for returning the universal bar 20.

The rack 19 is in the same place on the carriage as the usual column stop rack on the Underwood typewriter, and is easily substituted therefor. The decimal stop rods 16 may be the same as those usually employed in said typewriter. The levers 13 may be hung upon the same fulcrum 14 that is usually employed, and keys 11 may be conveniently placed back of the keyboard and in front of the type bars, as illustrated. The rods 31 with the cams 29 may be placed im-

mediately back of the stop rods 16, making a very compact structure, and they may be guided in the bracket 30, which is readily secured to the bracket 37, in which the stop rods 16 are usually guided. The levers 32, carrying the rear set of rods 31, may extend compactly beneath the levers 13 carrying the forward set of rods 16; and the keys or stems on the levers 13 (which are below the key-levers 2) may be in rear of the keys 33 on the lower levers 32. In other words, one system of keys, levers and rods, as 12, 13, 16, may nest within the other system of keys, levers and rods, thus making a very compact and satisfactory arrangement. Each cam 29 with its rods 31 may be formed by a single unbent stamping of sheet metal as illustrated, thus conducing to cheapness and compactness; and the cams 29, which overhang the rods, may rest upon the top of the bracket 30. The bracket may have upper and lower guides 38, 39 for the side edges of the rods, and the latter may have widened portions 40 to fit in said guides. As seen at Fig. 2, the several rods 31 may be variously cut away at their lower ends at 41 to clear the rear ends of the levers 32.

Each cam or plate 29 has a bevel portion 42, which is the first to engage the projections 28 as the carriage runs in letter-feeding direction; and it also has a horizontal dwell portion 43, which holds the projection 28 elevated while the column stop 18 passes by all the counterstops 17. The far end of each plate may also be beveled at 44, so that, if any cam is elevated while the carriage 6 is being run back, this bevel 44 will be engaged by the pin or pins 28, and the pin will ride up and pass freely over the cam, so that the return movement of the carriage is not obstructed. The final column stop 18^a may or may not be pivoted, as it is unprovided with any projection 28.

Each of the column stops is pivoted upon a mount 27, which is preferably in the form of a collar or box surrounding or fitted upon the column stop rack 19, which has beveled rack teeth 45 on its rear side. The mount is illustrated as comprising two portions, one of which is a body portion and has a top 46, front side 47 and bottom 48, to fit upon the top, front and bottom of the rack, and a cap portion 49, which fits upon the rear side of the rack and has a tongue portion 50, to fit between the top and bottom of the body portion. These portions of the box are fastened together by upper and lower screws 51, 26, the latter serving as a pivot for the column stop 18, which is mounted between opposite ears 53 extending down from the body of the box; the cap having a corresponding ear 54 into which the screw 26 is threaded. The tongue portion 50 of the cap is grooved longitudinally to fit over the row of rack teeth 45, which project

from the rear side of the bar 19 between the top and bottom edges thereof. A dog 55 has a stem 56 and button 57, and is pressed by a spring 58 into engagement with the rack teeth 45. The stem 56 passes through a boss 59 provided upon the cap, and the spring 58 is confined within said boss to press against the dog. The latter is circular in contour to fit the bore 60 in the cap; but at 61 to fit loosely between the top and bottom of the body portion of the box, so that rotation of the dog is prevented.

It will be seen at Fig. 7 that the flattened top and bottom sides of the dog are flush with the top and bottom surfaces of the tongue portion 50 of the cap. The top side 46 of the mount is preferably beveled down to an edge, as shown in the drawings, and this edge may coöperate with a scale 161 provided upon the top of the rack bar 19. To adjust the column stops, it is only necessary to pull the button 57 backwardly, thereby releasing the dog, whereupon the mount may be adjusted along the rack; and upon releasing the button, the spring 58 will reengage the dog with the rack.

Each column stop is preferably held down by means of a compression spring 62 having a seat 63 in the top of the dog and pressing up a ball 64 against the outer surface of the mount; a heel 65 on the dog limiting the downward movement thereof.

It will be seen that the column stops are not only very compactly arranged and very easily adjusted along the rack, but also that they may be very strong and rigidly supported.

Variations may be resorted to within the scope of the invention, and portions of the improvements may be used without others, as for instance the column stops and their mounts may be used with other varieties of counterstops.

Having thus described my invention, I claim:

1. The combination with a carriage, of a rack bar thereon, a plurality of mounts supported wholly upon said rack bar, and each adjustable therealong independently of the others in the direction of the run of the carriage, stops upon said mounts, certain of said stops pivoted and having rearwardly extending projections, said projections of graduated lengths, key-operated cams connected to said keys and placed one behind the other beneath the projections, one cam liftable by its key into the path of the longest projection to withdraw one of the stops, the next cam liftable by its key into the path of the two longest projections, to withdraw two of the stops, and so on throughout the series, and a counter stop.

2. The combination with a carriage, of a rack bar thereon, a plurality of mounts sup-

- 4
- ported wholly upon said rack bar, and each adjustable therealong independently of the others in the direction of the run of the carriage, stops upon said mounts, certain of said stops pivoted and having rearwardly extending projections, said projections of graduated lengths, cams placed one behind the other beneath the projections, one cam liftable into the path of the longest projection to withdraw one of the stops, the next cam in the path of the two longest projections to withdraw two of the stops and so on throughout the series, a series of upstanding rods to lift said cams, a series of levers controlling said rods and extending forwardly to the keyboard and having keys at their forward ends, and a counter-stop settable by any of said keys.
3. In a typewriting machine having a keyboard and type-key levers, the combination with a set of tabulator keys in rear of the keyboard, of levers extending rearwardly from said keys below the type-key levers, rods extending upwardly from said tabulator levers, a second set of tabulator keys in front of the first and extending rearwardly below the first set of tabulator levers, rods extending up from the rear ends of the second set of tabulator levers and in rear of the first rods, decimal stops carried by one set of rods at their upper ends, cams carried by the other set of rods at their upper ends, and column-stops on said carriage engageable by said decimal stops and releasable by said cams.
4. In a typewriting machine having a keyboard and type-key levers, the combination with a set of tabulator keys in rear of the keyboard, of levers extending rearwardly from said keys below the type key levers, rods extending upwardly from said tabulator levers, a second set of tabulator keys in front of the first and extending rearwardly below the first set of tabulator levers, rods extending up from the rear ends of the second set of tabulator levers and in rear of the first rods, decimal stops carried by one set of rods at their upper ends, cams carried by the other set of rods at their upper ends, and column-stops on said carriage engageable by said decimal stops and releasable by said cams, one of the decimal-stop rods having a lug operable by all the rods in the other set.
5. The combination with a bar having rack teeth thereon, of a mount fitted upon said bar and adjustable therealong and comprising two portions detachable from each other and clasping the bar, a releasable dog arranged in said mount to engage the rack, a stop upon said mount and movable relatively thereto, and a counter-stop.
6. The combination with a bar having rack teeth thereon, of a mount fitted upon said bar and adjustable therealong and com-

prising a body portion fitted upon three sides of the bar, and a cap portion to close the box, means securing the cap portion to the body portion, a releasable dog arranged on said cap portion to engage the rack, a stop pivoted on said mount, and a counter-stop.

7. The combination with a bar having rack teeth thereon, of a mount fitted upon said bar and adjustable therealong, said mount in the form of a box fitted upon said bar and comprising two portions, one of which has a top, side and bottom to fit upon the bar, the other of which is a cap, means detachably securing said cap to said body portion, said cap having a tongue portion to fit between the top and bottom of the body portion, said tongue portion grooved longitudinally to fit over the rack teeth, a dog engaging said rack teeth and having a stem, a boss upon the cap through which said stem passes, a spring confined within said boss to operate said dog, and a withdrawing button on said stem; said dog arranged in a circular seat in the cap, and the dog flattened to engage the body portion of the box, so that rotation of the dog is prevented.

8. The combination with a bar having rack teeth thereon, of a mount fitted upon said bar and adjustable therealong, said mount in the form of a box fitted upon said bar and comprising two portions, one of which has a top, side and bottom to fit upon the bar, and the other of which is a cap, a device fastening said cap to said body portion, a column stop pivoted upon said fastening device, a spring between said dog and said box, and means to limit the movement of the dog upon its pivot.

9. The combination with a bar having rack teeth thereon, of a mount fitted upon said bar and adjustable therealong, said mount in the form of a box fitted upon said bar and comprising two portions, one of which has a top, side and bottom to fit upon the bar, and the other of which is a cap, said cap having a tongue portion to fit between the top and bottom of the body portion, devices securing said cap to said body portion, said tongue portion grooved longitudinally to fit over the row of rack teeth, which project from said bar between opposite edges thereof, a dog engaging said rack teeth and having a stem, a boss upon the cap through which said stem passes, a spring confined within said boss to operate said dog, a withdrawing button on said stem, said dog arranged in a circular seat in the cap, the top and bottom of the dog flattened to fit loosely between the top and bottom of the body portion of the box, so that rotation of the dog is prevented, one side of said mount beveled to co-operate with a scale provided upon said rack bar, a column stop pivoted upon one of said fastening devices, said column stop

mounted between ears extending from the box, a spring between said stop and said box, and means to limit the movement of the stop upon its pivot.

- 5 10. The combination with a bar having rack teeth thereon, of a mount fitted upon said bar and adjustable therealong and comprising a body portion fitted upon three sides of the bar, and a cap portion to close 10 the box, means securing the cap portion to the body portion, a releasable dog arranged

on said cap portion to engage the rack, a stop pivoted on said mount, and a counter-stop; said stop on said mount having a projection arranged to be moved to lift the stop 15 to an ineffective position when it is to clear a projecting counter-stop.
